SHUTTLE TENSION

Filed March 3, 1936

UNITED STATES PATENT OFFICE

2,107,917

SHUTTLE TENSION

William A. Tebo, Anthony, R. I.

Application March 3, 1936, Serial No. 66,839

5 Claims. (Cl. 139—217)

This invention relates to weaving shuttles and has for one of its objects the provision of an improved yarn tension device for applying tension to the filling yarn in such a way as to permit the yarn to be threaded into the shuttle eye more easily than in any prior tension devices which provide for an equivalent amount of tension.

Another object of the invention is to provide for so dividing the total tension among a plurality of tension-applying units that, if one unit should become unthreaded or ineffective for its intended purpose, sufficient tension will still be applied to the yarn by the other unit or units to prevent serious defects in the fabric, and so that each such individual unit need not grip the yarn so firmly as when a single unit only is employed whereby slubs or knots are enabled to enter and pass through the tension device without breaking the yarn or causing shiners in the cloth, defects commonly resulting from excessive tension such that knots or slubs catch in the tension device and are retarded thereby.

Further objects of the invention are to provide tension means which will not tend to push the twist back, when hard twisted yarn is utilized; to provide tension means such as to prevent breakage of a filament or filaments when multi-filament yarn is employed; to provide an improved tension device such that slack picks will not occur; to provide a tension device such that the fur tension, which is commonly provided in shuttles for weaving certain types of goods, may be reduced in amount or eliminated, thus permitting the shuttle, especially when of automatic type, to be more easily threaded and also avoiding the necessity of combing up or rejuvenating the fur at frequent intervals, as is necessary when a fur tension is used; and to provide a tension of a type which will distribute the tensioning pressure upon the yarn over a substantial length of the yarn as it is drawn from the bobbin in the shuttle chamber, instead of localizing the pressure at one point, as is common.

Other objects and advantages of the invention will be made manifest hereinafter in the following more detailed description and by reference to the accompanying drawing in which:

Fig. 1 is a top plan view of one end portion of an automatic shuttle showing my improved tension means in position;

Fig. 2 is a top plan view of the threading block removed;

Fig. 3 is a section on the line 3—3 of Fig. 2;

Fig. 4 is a section on the line 4—4 of Fig. 3;

Fig. 5 is a perspective view of one of the tension members;

Fig. 6 is a perspective view of the opposite surface of one of the tension members, a pair of these forming one unit of the several tension units in the threading block;

Fig. 7 is a top plan view of the end portion of a hand-threading shuttle, showing a different block in place with my tension mounted in the block;

Fig. 8 is a top plan view of a fragmental portion of a regular shuttle, showing my tension mounted in the block inserted in the throat portion of the shuttle;

Fig. 9 is a top plan view of the threading block of an automatic shuttle with a modified form of tension mounted therein;

Fig. 10 is a section on the line 10—10 of Fig. 9;

Fig. 11 is a section on the line 11—11 of Fig. 10;

Fig. 12 is a perspective view of one of the tension members, showing its face-engaging surfaces for contacting the yarn, and the bar connecting the members;

Fig. 13 is a sectional view similar to Fig. 3, but modified by showing springs on both of said pairs of tension members.

In the use of shuttles, considerable difficulty has been experienced with the tension at the throat portion adjacent the bobbin chamber which sometimes interferes with the threading of the shuttle or where inferior yarn is being used causes knots or slubs in the yarn to break the yarn or else to cause shiners in the cloth; also, some tension may become unthreaded causing a slack pick which ruins the cloth. Such difficulty in threading is particularly detrimental and noticeable in automatic shuttles where the yarn enters and threads automatically when one bobbin is transferred into the shuttle to replace an empty bobbin, and various means have been experimented with to overcome these difficulties. At times some means have been inserted over which the yarn will drag, but this is unsatisfactory when the yarn rises and is out of contact with such friction surface. At times a friction has been used so that the yarn will engage the same at the time of the first pick, but after the yarn becomes threaded in the shuttle such tension no longer acts. In order to overcome these difficulties and provide improved tension, I have divided the mechanical tension which exists in shuttles into a plurality of parts and cause each of these parts to engage the yarn with less tension than a single mechanical unit heretofore provided, but the sum of the tension of the plurality of units or contacting surfaces will be equal to the tension

heretofore used or may, where cases require it, be increased without the detrimental effects which have heretofore been present in the increasing of the tension where a single mechanical unit has been used; and the following is a more detailed description of the present embodiment of this invention, illustrating the preferred means by which these advantageous results may be accomplished:

With reference to the drawing, I will first point out that the tension which is the subject of this invention, is applicable to the regular shuttle, the hand-threading shuttle and the automatic shuttle, and I have shown the invention in each one of these three types of shuttles, and have shown one modification in connection with an automatic shuttle, although it will be readily apparent that the same may be applied to the hand-threading or regular shuttle in a manner similar to that illustrated and spoken of above.

With reference to the drawing, 15 designates the body portion of the shuttle having a bobbin chamber 16 with a bobbin 17 positioned therein and a filling 18 wound on the bobbin. The eye 19 of the shuttle is designated 19 in Fig. 4 with guide posts 20 and 21 of porcelain or some wear-resisting material, as is usual.

The threading block 22 is of a known type except that it may be extended to provide a somewhat longer extent at the throat portion 23 to accommodate a plurality of friction units which are the subject of this invention. In threading, the yarn 24 as it is drawn from the bobbin 17 is caused first to be drawn down under the horns 25 on the first pick and then into the eye 19 of the shuttle on the second pick of the shuttle, in a known manner.

In this extended portion 23 of the threading block 22 there are arranged two or more thread tensioning devices each comprising a pair of thread-engaging elements designed to contact opposite sides respectively of the thread on its way from the bobbin chamber to the shuttle eye, each such element being of substantially the structure shown in Fig. 5 and Fig. 6. The body portion of each element 26 is flanged as at 27 and provided with an opening 28 of a sufficient size loosely to mount the elements 26 upon a pin 29 having an enlarged threaded head portion 30 slotted as at 31. This head engages a threaded bore 32 in one side wall of the block 22, the opposite end entering a bore 33 in the opposite side wall for firmly mounting this pin in position.

The upper end of each of the members 26 is directed backwardly as at 34 from the face 35 of the member and enters an opening 36 in a bushing 37 supported in a bore 38 in the side wall of the block at its portions 23, and each of these backwardly extending portions 34 is flanged as at 39 so as to engage and both to support and guide the member and permit it to be movable to some extent in its mounted position.

One of the members 26 engages an abutment stud 40 to prevent its movement in one direction to any substantial extent from the center line which it is desired that the thread shall travel; while the other member 26 is backed up by a spring 41 urged with the desired tension by a screw 42 threaded into a bore in the side wall of the block and slotted as at 43 for adjustment, the screw being recessed or cupped at its inner end to receive the spring therein and centralize it that it may direct its pressure in the desired direction.

The pair of members just described constitute

one unit which I will designate generally 45 and I multiply these units in any desired number, there being shown a second unit 46, see Fig. 2, although additional units may be provided whereby the tension is distributed rather than localized in one place.

In Fig. 7 the hand threading shuttle 52 is shown as having the throat portion 51 which is necessarily of a shape different from that of the shuttle using the automatic threading block, but the block 50 is also removable and contains tension units 45 and 46 which are substantially identical with the threading units just described.

In Fig. 8 I have illustrated a regular shuttle 54 having a block 56 for supporting the tension units 45 and 46 which are identical with the units 45 and 46 of the automatic shuttle above described. Here, of course, the thread is passed into the throat 57 and a hook is used to draw the thread through the shuttle eye.

In Figs. 9, 10, 11 and 12 a different or modified form of tension is shown. In this arrangement a duplex tension member is disposed at each side of the thread on its way through the shuttle, each such duplex tension member comprising a pair of spaced thread-engaging elements 61 and 62 which are rigidly joined together as by a bar 60. The bar 60 is set back from the plane of the thread-engaging surfaces of the elements 61 and 62 so as not to engage the thread. A threaded abutment stud 63 is provided to back up each of the elements 61 and 62 which are at one side of the thread while a single spring 64 is arranged to engage the bar 60 on the other side and to force the two thread-engaging elements 61 and 62 to which it is attached toward their corresponding opposed members. This spring reacts between a block 65 and the bar 60 and the block 65 may, if desired, be adjusted longitudinally of the shuttle by a screw 66 having a slotted head 67. This screw passes through the block 65, and its inner end is mounted for rotation in a suitable bore 68 in the side wall 23 of the block 22 and is held in adjusted position by a set screw 69. By this means a single spring serves to apply the tension to the several tension devices, and the relative tension exerted by the respective pairs of opposed thread-engaging elements may be varied merely by sliding the spring along to cause it to bear against the bar 60 nearer to one end than the other of the latter. Abutment studs 63 in this case may be adjusted to vary the total tension. If desired, additional adjusting means may be interposed between the spring and the block 65. A vertical slot 70 in one side wall of the block facilitates the assembly of the tension device with the block.

As a modification of the construction of Fig. 3, abutment springs 41, adjustable by members 42, may be positioned back of each of the members 26 at positions corresponding to those of the studs 40 or 63, which will assist in easy threading of the tension members and in an easier action when a slug or knot comes in contact with the tension members.

By this arrangement of tension I may adjust either pair of members individually, as shown in Figs. 1 to 6, so as to provide the same or different tensions. It is somewhat preferable to have a gradually increasing tension, as this facilitates easy threading. However, in some cases it may be preferred to have the same tension at both pairs of units. The arrangement illustrated in Figs. 10 to 12 inclusive provides for relatively varying the tension between the two tension de-

vices by moving the single spring along the bar so as to exert more tension at one of the tension devices than at the other, thus permitting a gradually increasing or a gradually decreasing tension to be secured, as desired.

5 The improved constructions herein described not only make the shuttle easier to thread but are easier on the yarn, thereby resulting in less breakage, particularly when filament yarns of the 10 artificial cellulose derivative type are employed for the reason, as above pointed out, that slubs or knots in the inferior grades of yarn are permitted to pass without breaking the yarn or causing shiners such as result from excessive 15 friction and tension.

The foregoing description is directed solely towards the construction illustrated, but I desire it to be understood that I reserve the privilege 20 of resorting to all the mechanical changes to which the device is susceptible, the invention being defined and limited only by the terms of the appended claims.

I claim:

1. In a shuttle having a bobbin chamber, a 25 thread eye, a plurality of spaced mechanical tension devices for engaging the yarn in working position, each tension device comprising a pair of thread-engaging elements mounted for movement toward and from each other, spring means 30 common to the several tension devices operative to urge the elements of each pair toward each other, means for adjusting the tension applied by the spring means so as simultaneously to vary to the same degree the tension exerted by each pair 35 of elements upon the thread, and means for moving the point of application of said spring means with reference to the several pairs of elements thereby relatively to vary the tension exerted by the respective tension devices.

40 2. In a shuttle having a bobbin chamber, a thread eye, a plurality of spaced pairs of thread-engaging elements having friction surfaces for engaging and squeezing the thread between them, a bar joining the several elements which are dis-

posed at one side of the thread, and a second bar joining the several elements which are disposed at the other side of the thread, said bars being constructed and arranged to receive applied force and to transmit it to each of the tension 5 elements connected to the respective bar.

3. In a shuttle having a bobbin chamber, a thread eye, a plurality of spaced pairs of thread-engaging elements having friction surfaces for engaging and squeezing the thread between them, 10 a bar joining the several elements which are disposed at one side of the thread, a single spring engaging said bar, the spring being operative to urge both of the elements connected to the bar toward the opposed elements, and means for adjusting said spring longitudinally of the bar thereby relatively to vary the tension exerted by the several pairs of elements.

4. In a shuttle having a bobbin chamber, a thread eye, a plurality of spaced pairs of thread-engaging elements having friction surfaces for engaging and squeezing the thread between them, 20 bars rigidly joining the several elements which are disposed at opposite sides of the thread, respectively, whereby force applied to either bar 25 is transmitted to the elements joined to said bar, resilient means engaging one bar, and adjustable but non-resilient means engaging the elements united by the opposite bar for varying the normal positions of said elements.

30 5. In a shuttle having a bobbin chamber and a thread eye, a plurality of pairs of spaced tension plates for engaging the yarn in working position, the plates of each pair being constructed and arranged to engage the opposite sides of one 35 section of the yarn, and yieldable means for urging one of the plates of each pair toward the opposite plate, said means and the plates being arranged so that the plates impose different and progressively increasing tension on the yarn passing between the plates of successive pairs on its way from the bobbin chamber to the eye.

40 WILLIAM A. TEBO.
